The ornamental design for a sensor with indicator, as shown and described.

DESCRIPTION

FIG. 1 is a side perspective view of a first embodiment of a sensor with indicator;

FIG. 2 is a top plan view of the sensor with indicator of FIG. 1;

FIG. 3 is a back plan view of the sensor with indicator of FIG. 1;

FIG. 4 is a front elevation view of the sensor with indicator of FIG. 1;

FIG. 5 is a back elevation view of the sensor with indicator of FIG. 1;

FIG. 6 is right side elevation view of the sensor with indicator of FIG. 1;

FIG. 7 is a left side elevation view of the sensor with indicator of FIG. 1;

FIG. 8 is a side perspective view of a second embodiment of a sensor with indicator;

FIG. 9 is a top plan view of the sensor with indicator of FIG. 7;

FIG. 10 is a back plan view of the sensor with indicator of FIG. 7;

FIG. 11 is a front elevation view of the sensor with indicator of FIG. 7;

FIG. 12 is a back elevation view of the sensor with indicator of FIG. 7;

FIG. 13 is right side elevation view of the sensor with indicator of FIG. 7;

FIG. 14 is a left side elevation view of the sensor with indicator of FIG. 7;

FIG. 15 is a side perspective view of a third embodiment of a sensor with indicator;

FIG. 16 is a top plan view of the sensor with indicator of FIG. 13;

FIG. 17 is a back plan view of the sensor with indicator of FIG. 13;

FIG. 18 is a front elevation view of the sensor with indicator of FIG. 13;

FIG. 19 is a back elevation view of the sensor with indicator of FIG. 13;

FIG. 20 is a right side elevation view of the sensor with indicator of FIG. 13; and,

FIG. 21 is a left side elevation view of the sensor with indicator of FIG. 13.

The broken lines appearing in the drawings are for the purpose of illustrating portions of the article in which the design is embodied. Portions of the article appearing in broken lines form no part of the claimed design.
